CLAIM

The ornamental design for a combination light object and base, as shown and described.

DESCRIPTION

FIG. 1 is a perspective view of a combination light object and base showing a new design;

FIG. 2 is a front view of the combination light object and base of FIG. 1;

FIG. 3 is a top view of the combination light object and base of FIG. 1;

FIG. 4 is a bottom view of the combination light object and base of FIG. 1;

FIG. 5 is a rear view of the combination light object and base of FIG. 1;

FIG. 6 is a right side elevational view of the combination light object and base of FIG. 1; and,

FIG. 7 is a left side elevational view of the combination light object and base of FIG. 1.

The broken lines showing feet appearing in FIGS. 1 and 4-7; switch buttons appearing in FIGS. 1 and 3; and an electric adapter appearing in FIGS. 4 and 7 are for the purposes of illustration only, and form no part of the claimed design.

1 Claim, 4 Drawing Sheets
